METHOD OF DISTRIBUTING AIR

Alfred E. Stacey, Jr., Essex Fells, and Charles E. Ernst, Elizabeth, N. J., assignors, by mesne assignments, to Carrier Engineering Corporation, Newark, N. J., a corporation of New York

Application July 27, 1932, Serial No. 624,956

1 Claim. (Cl. 98—40)

This invention relates to an improved method and means for introducing air into an enclosure for atmospheric conditioning purposes.

In the art of air conditioning, air is usually introduced into an enclosure hotter or colder than the air in the enclosure, depending on whether heating or cooling is desired. That is, there must be a temperature differential between the introduced air and the room air. Obviously, a large quantity of introduced air at a small differential will give the same resultant temperature effect as a small quantity of introduced air having a large differential. From an economic standpoint, however, the latter method is preferable, because smaller ducts to convey the introduced air may be used, as well as smaller fans, motors, conditioning apparatus and auxiliaries, thereby saving money in construction and, more important, saving space. Furthermore, the conditioned air may be delivered to outlets at a higher pressure, thereby still further enabling reduction in the size of delivery ducts. Although it has long been recognized that a material saving could be realized by introducing a small quantity of air at a large temperature differential into an enclosure, this method has not been generally adopted, because its application has heretofore been accompanied by various troubles, principally drafts and the production of noise.

An object of the present invention is to provide a method of air distribution whereby an enclosure may be conditioned satisfactorily by the introduction of air with a large temperature differential.

Another object is to provide a method of conditioning the air within an enclosure without causing drafts, streaks, or uneven temperature conditions.

A further object of the invention is to provide a means for utilizing air at a relatively high pressure in an air conditioning system without causing objectionable noise.

A feature of the invention resides in the provision of a plurality of openings arranged in an outlet panel, each of the openings having means for allowing air easily to pass therethrough with a minimum of noise.

Another feature of the invention resides in the formation and grouping of a series of openings at the outlet to a supply duct whereby the noise of air transmission and discharge is substantially wholly or in greater part reflected back within the duct and prevented from entering the enclosure served by the duct.

A further feature covers the arrangement of

a plurality of openings in an air outlet structure and the proportioning of the area of each opening with respect to the solid area surrounding the opening, whereby the air in the enclosure served by the structure will be adequately recirculated and mixed with the conditioned air to form a series of tempered streams resulting in air movement and the imparting of equable air conditions throughout the area served.

Another feature enables the use of slots or narrow openings in a plurality of different arrangements in outlet structures whereby the requirements of varying types of air conditioning systems and air distributing conditions will be met.

Other objects and features of the invention making for simplicity and economy in manufacture and installation and providing efficiency in air distribution and air conditioning operation will be more apparent from the accompanying description of typical forms of the invention to be read in connection with the accompanying drawings, in which:

Fig. 1 is a plan view of an air outlet adapted to carry out the objects of the invention.

Fig. 2 is a plan view of a modified form of the invention.

Fig. 3 is a sectional view of Fig. 1 on the line 3—3, showing the outlet mounted in an air conduit, and

Fig. 4 is a vertical section of an enclosure, in diagrammatic form, illustrating the air circulation obtained with an adaptation of applicants' method and means of distributing air.

In the drawings, similar designations referring to similar parts, 5 is a plate, preferably of metal, although wood, bakelite, or similar material can be used, having a series of slots 6 therein. The slots 6 are spaced apart, and it has been found desirable in practice to have the spacing between the slots from 2 to 5 times as great as the width of the slot. To prevent the creation of noise apt to result from the rush of air through the plate, it is highly important that the inner side of the plate present as smooth a surface as possible to the flow of air, and this is accomplished by turning the edges of the slots outwardly, as shown in Fig. 3. As a result, a series of individual nozzles 7 are formed. Although it is apparent that a large number of small circular nozzles could be punched in a plate in a similar manner, applicants prefer the slotted type shown in the drawings, for reasons hereinafter set forth.

The plate 5 has holes along its edges through which screws 8 may be inserted to hold the plate,

- which covers the end of an air duct 9, in place. As shown in Fig. 3, the plate is attached to flanges 10 formed on the ends of duct 9. Between plate 5 and flanges 10 is preferably inserted a layer of felt or cork 11.
- To provide a damper or closure member so that part of the slots may be covered, for purposes hereinafter explained, a flat plate 12 is hinged or otherwise pivotally attached to plate 5.
- 10 A covering of felt or similar material is preferably placed over the plate 12. Fastened to 5 and resting on the duct 9 is a flat relatively deep angle piece 13. A threaded bolt 14 is journaled at its head end near the bottom of plate 5 and 15 near its other end in the upright part of angle 13. A nut 15 is locked, in any convenient manner, on the end of the bolt, so that the bolt and nut may be turned, but without withdrawing the bolt. Threaded on the bolt 14 is a cup shaped 20 angle iron 16 having a projection 17 against which the damper plate 12 may rest. Obviously, a flat threaded block, or similar device, having a projection similar to 17 could be substituted for 16. The angle piece 16 is sufficiently deep so that 25 it rests upon the long leg of piece 13, but is not attached thereto, and is of sufficient width so that it will not turn. Therefore, upon turning the bolt 14 and the nut 15, locked thereto, the piece 16, since it cannot rotate, will either advance or retreat, depending on the direction of rotation of the screw. If, for example, 14 is rotated clockwise, 16 will advance toward plate 5, and projection 17, resting against the hinged damper 12 will swing the damper towards its 30 closed position. Conversely, rotating bolt 14 counterclockwise will cause 16 to retreat and the damper will open. If desired, a spring may be attached to the damper 12 to hold it firmly against projection 17.
- 40 The method of operation is as follows. Air from a suitable source is introduced in the duct 9 at a relatively high pressure. For example, the outlet has been used with air having a static pressure of .8" water. The air will pass through 45 the slots 6 and be discharged by the nozzles 7 in relatively thin sheets. Upon discharge from the nozzles, the velocity of the air will be greatly increased with a consequent drop in pressure, hence, producing an area of low pressure surrounding each thin stream of air. As indicated 50 by the arrows on Fig. 4, the streams of air, due to their velocity, will carry a relatively great distance before beginning to diffuse downwardly toward the floor. The room air will move into 55 the low pressure area surrounding the individual air streams and will be entrained and mixed with the high velocity air, hence, tempering the introduced air before it reaches the zone of occupancy in the room. Applicants have found that 60 the amount of air entrained by a high velocity jet is a function of surface area of the air stream, that is, a function of the perimeter of the jet. Hence, to secure entrainment of a relatively large volume of room air for each volume of conditioned air introduced, the ratio of the perimeter of the jet to the area of the jet must be relatively large. This ratio is hereinafter referred to as the "perimeter-surface ratio". In practice, applicants secure the necessary ratio by introducing air through narrow slotted nozzles, the 70 ratio of the perimeter of the nozzles to the free area of the nozzles being relatively large. Thus, a quantity of primary air, introduced into the enclosure in the form of thin sheets, presents 75 a relatively large perimeter surface to the air

in the room, and so induces the circulation of a relatively large volume of secondary air. Because of the large number of small streams, and the consequent large perimeter-surface ratio, a larger amount of room air will be recirculated 5 or entrained with the conditioned air than has been possible with previous types of discharge means. Thus, with this device, smaller quantities of supply air may be introduced into the enclosure at larger temperature differentials than 10 has heretofore been possible, and higher pressures may be used.

By turning the edges of the slots in well rounded curves, as shown in Fig. 3, and by breaking the air stream up into a large number of 15 small streams, it has been found that whistling and other noises usually encountered with high pressure, high velocity outlets has been substantially entirely overcome.

The formation of slots 6 in plate 5 enables 20 proper proportioning between the aggregate area of the slots and that of the plate surrounding the slots. As may be noted in Figs. 1 and 2, the solid area of the plate is greater than that of the slots, and this solid area serves to reflect back 25 into the duct a great part of the noise incident to air transmission through the duct to the outlets. Although this solid area is provided for this purpose, the free area, comprising the slot openings, is sufficient to permit a volume of air to be 30 delivered adequate for conditioning and circulation purposes. The provision of slots in the form of nozzles having rounded edges does not interfere with the delivery of air at desired high velocities, and at the same time, assures freedom 35 from whistling and kindred noise.

A duct 18 is shown in Fig. 4 through which part of the air from the room may be exhausted. This air may be returned to a conditioning device or it may be disposed of in any other de- 40 sired manner.

The damper 12 is used to adjust the amount of air issuing from the outlet. If, for example, this type outlet were used in a system designed to condition a number of rooms, it is quite probable that the rooms would not all be of the same size or require the same quantity of air. Device 12, therefore, serves as a throttling damper, and by opening or closing the damper, the quantity of air discharged and the distance which it will 50 carry may be regulated. In practice, the damper 12 will be set in one position and will remain there.

In some installations, it may be found desirable to provide a means to regulate the volume of air 55 either by hand operation or by automatic means, and at the same time maintain constant the distance through which the air will blow. For example, a room in which the number of people varies greatly would require a large quantity of air 60 at one time and at another time, it would require a smaller quantity. However, the length of the room has not changed and in order to prevent drafts, the distance through which the air will blow must be maintained. In this case, a damper, such as a slide, may be provided so that one or more of the slots may be completely closed without interfering with the remaining slots.

Fig. 2 shows a different arrangement of the slotted outlet described in connection with Fig. 1. 70 In this case, the slots are arranged as radii of a circle. The edges of the slots are turned in the same manner as was previously described in connection with Fig. 3, thereby forming a series of thin nozzles. This design is adapted to be em- 75

ployed in connection with round ducts, or it might be found desirable from an artistic point of view.

Although square and round types of outlets are illustrated, it is apparent that the same principles may be employed in connection with outlets variously formed and containing slots or series of slots in different positions and groupings.

Having described our invention, what we claim as new and desire to secure by Letters Patent is:

A method of distributing air within an enclosure which comprises supplying conditioned air to a

point adjacent the enclosure at relatively great static pressure, expanding said air substantially to the pressure existing within the enclosure, said air being expanded and discharged directly within the enclosure in the form of thin elongated high velocity streams in a direction substantially parallel to the floor of the enclosure, whereby air within the enclosure is induced to move and mix with the introduced air for the purpose of tempering the same.
